Atty.

UNITED STATES PATENT OFFICE.

JACOB S. BROWN, OF CARLISLE, PENNSYLVANIA, ASSIGNOR OF ONE-HALF
TO WILLIAM E. AND JOHN R. MILLER, OF SAME PLACE.

ATTACHMENT FOR ENGINES.

SPECIFICATION forming part of Letters Patent No. 367,784, dated August 9, 1887.

Application filed December 13, 1886. Serial No. 221,409. (No model.)

To all whom it may concern:

Be it known that I, JACOB S. BROWN, a citizen of the United States, residing at Carlisle, in the county of Cumberland and State of Pennsylvania, have invented certain new and useful Improvements in Attachments for Engines; and I do hereby declare the following to be a full, clear, and exact description of the invention, such as will enable others skilled in the art to which it appertains to make and use the same.

My invention relates to attachments for steam-engines; and it consists in the construction and arrangement of the parts of the same, which will be more fully hereinafter described, and pointed out in the claims.

One object of my invention is to provide means for reversing the motion of the engine, or, by a change in the position of the parts of the same device, to open and close the throttle-valve, or produce the two functions simultaneously, as may be required and desired.

A further object of my invention is to provide a device adapted to be operated to simultaneously reverse the engine or open and close the throttle-valve, which is simple and effective in its construction and operation, easily handled and readily understood, strong and durable, positive in its desired result, and comparatively inexpensive in its manufacture.

I attain these objects by the mechanism illustrated in the accompanying drawings, wherein like figures of reference indicate similar parts in the several views, and in which—

Figure 1 is a side elevation of a suitable frame-work mounted upon wheels, showing a boiler and vertical engine and my improved device in relative connection therewith. Fig. 2 is a detail view in perspective of my improved attachment.

This attachment is adapted for use in connection with any form of machine or engine as may be desired, but is more especially applicable for use in connection with my improved well drilling and boring machine, application for which was filed July 12, 1886, Serial No. 207,804.

In the drawings, 1 represents a frame-work, of any suitable construction and mounted on or propelled by other means than those illustrated in the drawings. In one portion of this

frame-work a boiler and furnace, 2, may be mounted, and in another portion thereof a vertical engine, 3, is situated, a supply-pipe, 4, running to said engine from the boiler, having a throttle-valve, 5, of suitable construction, and an exhaust-pipe, 6, running from the engine to the smoke-stack of the furnace of the boiler 2.

Secured to one portion of the side of the frame-work 1 are two uprights, 7, which support a metallic rod, 8, which is provided with a stud or pin, 9. The one end of said rod is constructed to pass into an aperture in a hand-wheel, 10, secured to one end of a sleeve, 12, on said rod, and the other end provided with a bevel-gear, 11. Mounted upon the rod 8 is an elongated sleeve, 12, having a slot, 13, formed therein, through which the stud or pin 9 on the said rod 8 protrudes flush with the outer surface of the said elongated collar. This sleeve 12 has a sliding movement on the rod 8, and is adapted for a purpose which will be more fully hereinafter described.

Formed integral with or otherwise secured to one portion of the sleeve 12 is a recessed collar, 13', which is adapted to receive one end of a small rod, 14, which is looped around the recessed collar 13' at one end, and thence passes down under the frame-work and suitably connected thereto, and is attached to the reversing-lever of the engine in any suitable manner. By drawing or pulling on the hand-wheel 10 the sleeve 12 slides outward on the rod 8, and such a motion is imparted to the lever, to which the rod 14 is connected, as to reverse the engine. This is due to the fact that the collar 13 is moved from its normal position, and consequently the lever is shifted or drawn toward the hand-wheel 10. When the hand-wheel 10 is pushed back again, the rod 14 resumes its normal position and the reversing-lever is thrown back and the engine caused to run as before being reversed.

On the end of the rod opposite to the one adjacent to the hand-wheel 10 a bevel-gear, 11, is mounted, which is adapted to mesh with a relatively situated bevel-gear, 16, mounted on an inclined rod, 17, at the upper end of which a bevel-gear, 18, is mounted, which in turn meshes with a bevel-gear, 19, mounted on the end of the stem 20 of the throttle-valve 5,

which is of any desired construction, but preferably in the form of a two-way valve. By turning the hand-wheel 10 the motion imparted thereby is transmitted through the rod 8 and the gear-wheel 15 on the opposite end thereof to the gear 16 on the lower end of rod 17, and from thence to the gear 18, to gear 19 on the valve-stem 20, and thus open or close the valve 5 as the hand-wheel 10 is turned, and govern the flow of the steam to and from the engine. The stud or pin 9, passing through a slot, 13, governs the extent to which the elongated sleeve 12 may be withdrawn and pushed back, the two ends of the slot bearing 15 against the stud or pin in either position. The slot 13 is constructed of such length as to allow the reversing-lever to be drawn or pushed from one side to the other to such a distance as to just produce the desired result.

20 This device or attachment is specially intended and applicable for use in connection with a well-drilling machine to regulate the raising or lowering of the drill and preventing accident to life and machinery, which frequently occurs, due to the heretofore uncontrollable action of the drill, especially when being raised to the surface.

It is obvious that slight variations in the construction and arrangement of the several 30 parts of the device could be made and substituted for those shown and described without in the least departing from the nature and principle of my invention.

Having thus described my invention, what 35 I claim as new, and desire to secure by Letters Patent, is—

1. In an attachment for engines, the combination, with the boiler, engine, and feed-pipe in connection therewith, of a rod, and an elongated sleeve partially incasing said rod, said

parts having connection with the throttle-valve and engine-reversing rod or lever, respectively, and constructed to be operated together or independently, substantially as described.

2. In an attachment for engines, the combination, with the boiler, engine, and feed-pipe in connection therewith, of standards mounted on one side of a suitable supporting framework, a rod mounted and supported by said standards, having suitable connections with 45 the throttle-valve, an elongated sleeve surrounding a portion of said rod, having a rod running therefrom to the reversing-lever of the engine, and a hand-wheel for operating the several parts, substantially as described. 50

3. In an attachment for engines, the combination, with the boiler, engine, and feed-pipe connected therewith, of standards mounted on one side of a suitable supporting frame-work, a rod having a stud-pin thereon, mounted in 60 and supported by said standards, and having gearing meshing with relatively-situated gearing on an inclined rod running to and connecting with the stem of a throttle-valve by means of suitable gears, an elongated sleeve 65 having a slot therein mounted upon said rod, the stud-pin of which engages with the slot in said sleeve, a recessed collar integral with or secured to said elongated sleeve, a rod or lever engaging said recessed collar and extending 70 down under the frame-work, and adapted to be attached to the reversing-lever of the engine, and a hand-wheel for operating the several parts, substantially as described.

In testimony whereof I affix my signature in 75 presence of two witnesses.

JACOB S. BROWN.
